UNITED STATES PATENT OFFICE.

CHARLES SEYBOLD, OF DAYTON, OHIO, ASSIGNOR TO THE HARRIS-SEYBOLD-POTTER COMPANY, OF DAYTON, OHIO, A CORPORATION OF DELAWARE.

CLAMP FOR PAPER-CUTTING MACHINES.

Application filed January 17, 1927. Serial No. 161,520.

My invention relates particularly to a device for controlling the return of the clamp to its raised position after the clamping and cutting operation.

It has been customary in the past by a counterweight or spring to return the clamp to a fixed raised position after each operation, and as a result, where packages of paper are being cut in piles of practically uniform thickness of say six inches with each operation, and the clamp has a normal throw of say 24 inches, there is a waste of travel of some 18 inches. Moreover, it is of advantage to utilize the clamp as a gauge for the pile of paper to be cut, and the clamp has to be lowered to the paper to serve as such gauge.

It is the object of my invention to remedy this waste of time in operation by the provision of a stop device for the return movement of the clamp, which can be readily and easily adjusted for any thickness of pile, so that while the down movement will not be affected, the operator, if he is cutting piles of any particular thickness, may regulate and control the return of the clamp to a point over the piles just sufficient to permit the sliding into the machine of the next pile.

The invention consists of that novel construction and arrangement of parts to be hereinafter particularly pointed out and claimed, whereby the above mentioned results are attained.

In the drawings:—

Figure 1 is a rear elevation of a portion of the clamp with stop device attached.

Figure 2 is a vertical section on the lines 2—2 of Figure 1.

The device can be readily and easily applied to any construction of clamp, and I have only illustrated the parts necessary to make clear the invention. The cross frame of the machine is indicated at 1, while 2 is the clamp and 2^a the knife which reciprocate in suitable guides in the side standards operable by power or foot treadle in any well known way.

Attached to the clamp at any convenient point is a link 3 which is coupled by a crank arm 4 to a disk 5, which in turn is mounted on a screw threaded stud bolt 6. This stud bolt has a squared medial portion 7 which fits in a correspondingly squared recess in the frame.

Mounted on the projecting squared portion of the stud are disk plates 8 and 9.

The disk 5, which is free to turn on the threaded end of the bolt 6, when turning in one direction will simply unscrew from the bolt, while in turning in the opposite direction, the disk will screw up on the bolt and come into friction contact with the plates 8 and 9. By adjusting the position of the disk 5 by the handwheel 10 on the screw threaded opposite end 11 of the bolt the point at which the friction of the plates will form a positive stop, can be readily obtained. The threads on the inner end of the bolt 6 are so formed that when the disk 5 rotates in a counterclockwise direction it will unscrew and thus no friction will occur when the clamp is being lowered to the paper pile, but when the clamp is being raised by its counterweight or otherwise, the disk will be screwed on the bolt to bring the disk 5 against the friction plates.

It will be obvious that the stop can be readily adjusted to automatically stop the upward movement of the clamp at the point desired, and that this stop will be maintained for each movement of the clamp until the operator adjusts the hand wheel 10 for some other stop position by removing the disk 5 farther from the friction disks or closer thereto.

Having thus described my invention what I claim as new and desire to secure by Letters Patent is:—

1. In a paper cutter provided with a clamp, of a clutch mechanism mounted intermediate the frame of the machine and the clamp, with means to adjust the clutch to stop the clamp at any desired position on its return stroke.

2. In a paper cutter provided with a clamp, of a friction clutch mechanism mounted intermediate the frame of the machine and the clamp, with means to adjust the clutch to stop the clamp at any desired position on its return stroke.

3. In a paper cutter provided with a clamp, of a clutch mechanism mounted on the frame, with connection therefor with the clamp and means for adjusting the clutch to stop the clamp at any desired position on its return stroke.

4. In a paper cutter the combination with the frame, of a clamp adapted to reciprocate

therein, and a friction clutch device mounted on the frame, with connections therefor with the clamp, and adapted to engage the clamp at any desired position upon its return stroke to serve as a stop.

5. Mechanism for limiting the return stroke of a clamp for paper in a paper cutting machine comprising a fixed stopping member, and a rotatably mounted member threaded so 10 as to approach the fixed stopping member during its rotation, means connected with the clamp for rotating said rotatably mounted member, and a threaded member providing the axis of rotation of said rotatably mounted member.

6. Mechanism for limiting the return stroke of a clamp for paper in a paper cutting machine comprising a fixed stopping member, and a rotatably mounted member 20 threaded so as to approach the fixed stopping member during its rotation, means connected with the clamp for rotating said rotatably mounted member, a threaded member providing the axis of rotation of said rotatably mounted member, and means for controlling the position of said member.

7. Mechanism for limiting the return stroke of a clamp for paper in a paper cutting machine comprising a fixed stopping member, and a rotatably mounted member threaded so as to approach the fixed stopping member during its rotation, means connected with the clamp for rotating said rotatably mounted member, a threaded member providing the axis of rotation of said rotatably mounted member, and means for controlling the position of said member, said member being mounted at approximately a right angle to the direction of movement of said 40 clamp.

8. In combination with a paper cutting machine and a clamp for the paper reciprocable to and from the surface of paper to be cut, a member having a frictional bearing surface, and a rotatable member operatively connected with said clamp, rotatable in a plane at approximately a right angle to the

plane of movement of said clamp, and means of varying the plane of rotation of said rotatable member, said means comprising a 50 threaded connection adjustable to various planes at right angles to the line of movement of the clamp.

9. In a paper cutter the combination with the frame, of a clamp adapted to reciprocate 55 therein, a non-rotatable bolt secured in the frame, and non-rotatable friction disk plates on said bolt, with a screw threaded disk adapted to engage said friction plates, the bolt being screw threaded at its outer end and connection for said screw threaded disk with the clamp, whereby the movement of the clamp in one direction will unscrew said disk and movement in the opposite direction will apply the friction and stop the clamp 65 movement.

10. In a paper cutter the combination with the frame, of a clamp adapted to reciprocate therein, a non-rotatable bolt secured in the frame, and non-rotatable friction disk plates 70 on said bolt, with a screw threaded disk adapted to engage said friction plates, the bolt being screw threaded at its outer end and connection for said screw threaded disk with the clamp, whereby the movement of the clamp in one direction will unscrew said disk and movement in the opposite direction will apply the friction and stop the clamp movement, with means for adjusting the position of the screw threaded end of the 75 bolt to adjust the stop position for the clamp.

11. In a paper cutter, a clamp stop device comprising a squared stud fixedly mounted on the frame, with a portion of the stud 80 screw threaded and a crank mounted on the screw threaded portion with a link connecting the crank with the clamp, whereby the crank will turn freely on the stud when the crank is rocked in one direction with friction 85 disks on the stud to be engaged by the crank when the crank is rocked in the opposite direction to stop the crank.

CHARLES SEYBOLD.
